DESIGN FOR A DISPLAY CARTON

Montgomery F. McCulloch, Louisville, Ky., assignor to The Turner, Day & Woolworth Handle Company, Louisville, Ky., a corporation of Kentucky

Application March 9, 1940, Serial No. 90,793

Term of patent 7 years

To all whom it may concern:

Be it known that I, Montgomery F. McCulloch, a citizen of the United States, residing at Louisville, in the county of Jefferson and State of Kentucky, have invented a new, original, and ornamental Design for a Display Carton, of which the following is a specification, reference being had to the accompanying drawing, forming a part thereof, in which:

Fig. 1 is a front perspective view of a display carton, showing my new design;

Fig. 2 is a rear perspective view thereof, on a reduced scale.

Fig. 3 is a sectional view taken along the line 3—3 of Fig. 1; and

Fig. 4 is a sectional view taken along the line 4—4 of Fig. 1.

I claim:

The ornamental design for a display carton, substantially as shown.

MONTGOMERY F. McCULLOCH.
